UNITED STATES PATENT OFFICE.

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY.

HOT-AIR STOVE OR FURNACE.

Application filed July 31, 1925. Serial No. 47,183.

My invention relates to improvements in heating apparatus, and the same has for its object more particularly to provide a hot air stove or furnace which is simple in construction, efficient in operation and inexpensive to produce.

Further, said invention has for its object to provide an apparatus in which the heat absorbing and heat emitting portions are formed as a unitary structure or casting.

Further, said invention has for its object to provide a heating apparatus of the type specified in which the exposed wall portions are of such form and contour that the air as it is heated will, in following its natural course, be caused to impinge upon and contact closely with said wall portions in its passage through the apparatus.

Further, said invention has for its object to provide a heating apparatus of the type specified comprising a heat emitting element and an enclosing casing therefor whose adjacent wall portions are so formed with respect to said element that the same form passages for the air, the cross-sectional area of which is proportional to the volume and rate of flow of the air passing therethrough.

Further, said invention has for its object to provide a heating apparatus of the character specified in which the heat emitting portion is formed as a unitary casting having its wall portions which become hottest, so formed as to crowd or force, or so retard the air that the same will become thoroughly initially heated and expanded upon first entering the apparatus, and then further heated by its contact with the remaining portions of said walls, and by the heat radiated by the upper part of said walls.

Further, said invention has for its object to provide a heating apparatus of the type specified having the outer wall portions of its heat emitting portion curved to follow the normal direction of the flow of the heated air, and provided with a series of curved vertical, parallel ribs or vanes forming extended air heating surfaces.

Further, said invention has for its object to provide a heating apparatus of the type specified in which the air is received and heated and discharged at a uniform temperature, and at a substantially constant rate of flow.

Further, said invention has for its object to provide a heating apparatus in which

the heat emitting element, comprising the combustion chamber and fuel receptacle, and the ash pit, is so constructed as to emit the heat of combustion at a rate which will not cause or permit the casting, constituting said heat emitting element, to become overheated or impaired.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings forming part of this specification—

Figure 1 is a front elevation showing one form of heating apparatus constructed according to, and embodying my said invention;

Fig. 2 is a side elevation;

Fig. 3 is a top view;

Fig. 4 is a front view, partly broken away to disclose the interior construction;

Fig. 5 is a rear elevation of the heating element with the enclosing casing broken away;

Fig. 6 is a side elevation partly broken away and in section, taken substantially on the line 6—6 of Fig. 7;

Fig. 7 is a transverse section on the line 7—7 of Fig. 6;

Fig. 8 is a detail perspective view of the heating element, with the door frame detached therefrom;

Figs. 9 and 10 are detail perspective views showing a portion of the fire door opening and grill therefor, and the means for detachably supporting said grill;

Fig. 11 is an enlarged detail section showing the same parts illustrated at Figs. 9 and 10;

Fig. 12 is a detail horizontal section on the line 12—12 of Fig. 6, and

Fig. 13 is a detail section on the line 13—13 of Fig. 6.

In said drawings the invention is shown as embodied in a stove adapted to be placed within the room or chamber to be heated directly thereby, and in said drawing 10 designates the apparatus as a whole comprising an outer casing or jacket 11, and a heating element 12 arranged within and enclosed thereby.

- The heating element 12 is formed of cast iron, and may be made in several parts and secured together, but by preference the same is formed as a unitary casting and comprises
- 5 a reduced rectangular ash receptacle 12^b from the upper portion of which extends a hollow, substantially elliptical, portion 13 having straight front and back portions 14 and 15. The inner portion of said casting
- 10 forms a fuel receptacle 16 and combustion chamber 17. The heating element 12 is provided at its lower corners with integral feet 20, 20 whereby to support the same in slightly elevated position.
- 15 The ash receptacle 12^b is provided at its front with an opening 12^a, and the upper elliptical portion is provided with a fuel opening 13^a, which are enclosed by an integral rectangular frame portion 18 which is
- 20 divided by a horizontal member 19 arranged between said openings 12^a and 13^a.
- The lower edge of the frame portion 18 extends below the base of the ash receptacle 12^b.
- 25 The rear wall of the elliptical upper portion 13 of the heating element 12 is provided adjacent to its upper end with a smoke outlet 20^a having a collar 21. 22 denotes an elbow having a flange 23 whereby the same
- 30 is secured to the upper portion 13 of the heating element, over the collar 21. The elbow 22 is provided with a tubular portion 24 through which extends the upper end of a rod 25 having a head 26 in its upper end
- 35 engaging an eccentric 27 mounted upon the rear end of a shaft 28 supported in bearings 28^a upon the heating element 12. The forward end of said shaft extends to the front of the apparatus and is provided with
- 40 an operating handle 29 and a pointer 29^a working over an indicating plate 29^b secured to the front of the apparatus. The upper and lower ends of the rod 25 extend through, and are guided by brackets 30, 30^a, projecting from the rear wall of the heating element 12. The rod 25 is provided adjacent to its lower end with two separated shoulders or collars 31 between the lowermost of which and the bracket 30^a is provided a
- 45 spring 32 to maintain said rod in normally raised position.
- 33 denotes a lever pivotally mounted intermediate its ends upon the bracket 30^a. The lower end of said lever is bifurcated and
- 55 loosely engages the rod 25 between the collars 31 thereon, and to the upper end of said lever is pivotally secured a disk or damper 34 serving to control the fresh air inlet opening 23^a provided in the rear wall
- 60 of the ash pit 12^b.
- The lower half of the fuel opening 13^a is provided with a removably supported grill or louvre frame 37 comprising side members 38 united by inclined transverse members 39.
- 65 The side members 38 are provided adjacent

to the upper ends with sockets 40, and adjacent to their lower ends with studs 41, adapted to engage, respectively with studs 40^a, and sockets 41^a provided upon each of the adjacent vertical wall portions of the 70 fuel opening.

The grate is composed of a plurality of revoluble bars 42 which have their reduced rear ends supported in sockets 42^a provided in the rear wall of the heating element 12, 75 and their forward ends supported in a plate 43 secured to lugs 44 provided on the heating element 12 between the ash pit and fuel receptacle. The reduced forwardly projecting ends of the grate bars 42 have fixed 80 thereon intermeshing gears 45, and one of said ends is provided with a polygonal portion 45^a to be engaged by an operating handle.

The ash pit opening 12^a is provided with 85 a door frame 46 to which is pivotally secured a door 47, and to the front of the heating element 12, and surrounding the ash pit opening 12^a and fuel opening 13^a is secured a flanged frame 48 to which is pivotally secured a door 49. The door 49 serves simultaneously to control the fuel opening and enclose the door of the ash pit opening.

The metal jacket 11 comprises side members 51, a front member 52, a back member 53, and a top member 54 suitably secured together along their adjacent edges.

The front member 52 is secured by bolts to the large door frame 48, and the back member 53 is similarly secured to a flange 100 23 on the elbow 22 of the smoke outlet.

The side wall members 51 are provided at their lower portions with air intake apertures 55; and the entire top member 54 is provided with similar air outlet apertures 105 55^a.

The entire outer surfaces of the elliptical or curved side walls of the upper portion 13 of the heating element are provided with alternately deep and shallow parallel ribs 110 or fins 26, 26^a, which conform in outline to said side walls, and the entire outer side of the back is provided with similar deep fins 27^a.

The spaces between the side walls of the heating element 12, and the adjacent wall portions of the enclosing casing 11 form passages for the air to be heated. The side walls of the ash pit 12^b are vertical and parallel with the side walls of the casing but are farthest removed therefrom so as to provide a relatively large intake chamber or reservoir for the air to be heated, while the side walls of the body portion adjacent to, or directly above, said ash receptacle are closest to the side walls of the enclosing casing and then curve inward gradually towards and meet at the top of the heating element, thereby forming air passages each of which has a constricted entrance portion,

which tapers towards its outlet end at which point it is widest. As a result of this arrangement of the parts, an air passage is formed at each side of the apparatus having a relatively large intake chamber communicating directly with the outer air (room air) in which the entering air is at once slightly heated by contact with the walls of the heating element, and slightly 10 expanded, and thence forced into and through the constricted portion of the passage where, by contact with the hottest parts of the heating element the air will be further heated and expanded, and pass upwardly 15 into the gradually wider portions of the passage and become still further heated and expanded, by contact with the wall of said heating element 12 and by the heat radiated from said heating element, and finally 20 issue in highly heated state through the outlet openings 55^a in the top of the casing 11.

Having thus described my said invention, what I claim and desire to secure by Letters 25 Patent is:

1. A heating apparatus of the character specified comprising a heating element including a hollow body portion whose interior forms a fuel receptacle and combustion chamber, and an ashpit; said body having an apertured front providing access to said fuel receptacle, and said ashpit, a casing enclosing said heating element having an opening therein registering with the 30 apertured front portion of said body portion, and means for securing said casing along the edges of the opening therein to said body portion, substantially as specified.

2. A heating apparatus of the character 40 specified comprising a heating element including a hollow body portion whose interior forms a fuel receptacle and combustion chamber and an ashpit; said body portion having an apertured front providing access to said fuel receptacle and said ashpit, a frame surrounding the apertured portion of said front, means for securing said frame to said body portion in position over 45 said apertured portion, a casing enclosing said heating element having an opening therein registering with the opening in said frame, and means for securing said casing along the edges of the opening therein to said frame, substantially as specified.

55 3. A heating apparatus of the character specified comprising a heating element including a hollow body portion whose interior forms a fuel receptacle and combustion chamber and an ashpit; said body por-

tion having an apertured front providing 60 access to said fuel receptacle and said ashpit, a frame surrounding the apertured portion of said front, a peripheral flange on said frame, means for securing said frame to said body portion in position over said 65 apertured portion, a casing enclosing said heating element having an opening therein registering with the opening in said frame, and means for securing said casing along 70 the edges of the opening therein to said frame, substantially as specified.

4. A heating apparatus of the character specified comprising a heating element including a hollow body portion whose interior forms a fuel receptacle and combustion chamber and an ashpit; said body portion having openings therein communicating with said fuel receptacle and said ashpit, a frame having openings registering with the openings in said body portion, a 75 peripheral flange on said frame, means for securing said frame to said body portion in position over the openings therein, and a casing enclosing said heating element having an opening therein registering with the 80 openings in said frame, and means for securing said casing along the edges of the opening therein to said frame, substantially as specified.

5. A heating apparatus of the character 85 described comprising an integrally cast heating element having a hollow body portion whose interior forms a fuel receptacle and combustion chamber, and a relatively 90 constricted ash pit portion below said body portion; said body portion having normal front and back walls and side walls curving upwardly and inwardly over the top, vertical ribs on said back and side walls, a 95 casing enclosing said body and ash pit portions; said casing forming with said ash pit portion relatively large intake chambers for the air to be heated and forming with 100 said body portion air heating passages having a relatively constricted portion adjacent to said intake chamber and portions becoming gradually and progressively larger in cross-sectional area as the same approach the outlet portion thereof, air inlet means in said casing adjacent to said ash pit portion, and air outlet means at the upper portion of said casing, substantially as specified.

Signed at the city of New York, in the county and State of New York, this 14th day of May, One thousand nine hundred and twenty-five.

ANDRÉ M. MERTZANOFF.
